UNITED STATES PATENT OFFICE.

EMIL CORNELY, OF WASHINGTON, DISTRICT OF COLUMBIA.

EMBROIDERING AND SEWING MACHINE.

SPECIFICATION forming part of Letters Patent No. 250,325, dated November 29, 1881.

Application filed May 3, 1881. (No model.) Patented in France January 29, 1881, in Belgium February 4, 1881, and in England February 5, 1881.

To all whom it may concern:

Be it known that I, EMIL CORNELY, of Washington city, in the District of Columbia, at present a resident of Paris, in the Republic of France, have invented a new and useful Improvement in Embroidering and Sewing Machines, which improvement is fully set forth in the following specification.

Figure 1 represents an elevation of the improved machine, with certain parts thereof in sections. Fig. 2 illustrates, on an enlarged scale, the new ornamental seam produced by said machine. Fig. 3 represents an elevation of the mechanism to which the invention has special reference. Fig. 4 is a cross-section through line 9 10, Fig. 3; and Fig. 5, a plan of the mechanism shown in Fig. 3. Figs. 6 and 7 are vertical and horizontal views similar to Figs. 3 and 5, showing different dispositions 20 of certain parts. Fig. 8 is a section through line 11 12, Fig. 3.

My invention relates to certain improvements on the embroidering-machine for which Letters Patent were granted to me, as assignee of 25 Antoine Bonnaz, on the 10th day of November, 1868, No. 83,910, and has for its object the production by improved means of an ornamental embroidering-seam, which is obtained by the serpentine windings of a second thread 30 under the chain-stitch seam.

The construction and operation of the Bonnaz embroidering-machine being fully known, the drawings and descriptions are limited to the subject-matter of the present invention.

The letters of reference in the drawings for the like parts are, as far as it is possible, the same as those in the specifications of the patent of November 10, 1868, No. 83,910, September 2, 1879, No. 219,225, and June 8, 1880, No. 40 228,445, which show some of the mechanical elements of the present machine, but in different combinations and for different purposes.

As in the Patent No. 228,445, the second thread in this machine is conducted by a thread-carrier, *b*, Fig. 1, which is disposed in a similar manner to the one shown in Patent No. 228,445, and which receives its motion by means of the gears B L K and shaft *p*, shown and described in said Letters Patent, but with this 50 difference, that said thread-carrier, instead of turning around the needle in a continuous re-

volving motion, has an oscillating motion imparted to it, so that it lays its thread around and under the needle at each stitch of the machine, once to the right and once to the left. 55 This oscillating motion of the thread-carrier *b* is obtained in the following manner: A pinion, *N*, provided with oblique teeth on its circumference, is secured to the main shaft *D* of the machine, and drives a horizontal cog-wheel, *O*, of double the diameter of pinion *N*, which is secured to the shaft *P*, which turns in casting *A* of the machine. A crank, *U*², is secured to shaft *P*, and its pitman *V*² drives a slide-head, *F*, which is guided within suitable 60 ways, *C*, of the bed-plate *A*. The pitman *V*² is secured at one end to the crank-pin *f*, and at its other end to the slide-head *F*, by means of stud *g*.

The shape of the slide-head *F* is best shown 70 in Fig. 4. Its forked end *h* extends into a collar, *i*, on the sleeve *M*, Fig. 3. As the wheel *O* is turned by the revolution of the main shaft, the shaft *P*, crank *U*², and pitman *V*² impart a reciprocating motion to the slide-head *F*, and 75 consequently to the sleeve *M*, which latter is loosely set upon the shaft *W*, and thus slides on said shaft, forward and backward. The extremity of the sleeve *M* is provided with a helical gear, *R*, which acts upon a similar helical 80 gear, *T*, secured to shaft *p*, and thus communicates an oscillating motion to the thread-carrier *b*, by which it lays its thread under the needle-thread at each stitch of the machine, once to the right and once to the left. 85

With the universal-feed machine it is necessary for the thread-carrier *b* to follow the movements of the universal feed of the machine, which is governed from the crank-handle *S*, Fig. 1, through the gearing *r s v x y*, shaft *z*, 90 pinions *U V*, shaft *W*, and pinions *Y Z*, for whenever the direction of the feed is changed by means of crank-handle *S* the position of the thread-carrier *b* must change in a similar way, or it could not lay its thread in the path of 95 the needle. The desired movement is effected in the following manner: A part of the sleeve *M* is milled out square in its interior, so that a square nut, *n*, Figs. 3 and 8, will fit nicely within the hollow part thereof. The nut *n* 100 is screwed rigidly to shaft *W* by means of screw 2, so that when the crank-handle *S* is

turned the shaft W and nut n and sleeve M will be turned with it, and the screw-gear R will turn that of T, and consequently revolve shaft p, wheels K L B, and thread-carrier b. 5 The latter thus has a compound motion imparted to it, the one resulting from the operation of the wheels N and O, which impart to it the oscillating motion, and the other resulting from the crank-handle S, which turns it 10 always in the direction of the feed; but both these movements, although independent one of the other, do not interfere with each other, and the result is the production of the above-explained ornamental seam by means of a universal-feed embroidering-machine. 15

Figs. 6 and 7 show a modified disposition of the parts. Motion is communicated from the sleeve M to the shaft p by bevel-gears R and T, and the compound motion before referred 20 to is imparted to the sleeve M by means of a screw and nut. The sleeve Q, which is actuated by slide-block F, is provided with a screw-nut, H', which by its reciprocation imparts to screw R' of sleeve M an oscillating motion on shaft 25 W, which is communicated to the thread-carrier b by means of bevel-gears R T, shaft p, and wheels K L B, while at the same time any motion of the crank S is transmitted to the thread-carrier b through screw-nut H' and 30 screw R'. The ornamental seam obtained is represented at Fig. 2; the chain-stitch is represented in unshaded and the second serpentine thread in shaded line. The thread-carrier b receives its thread from spool G, Fig. 1. The 35 thread descends from said spool through the hollow needle-bar o, and escapes from a hole in nipple-tube H, whence it is passed through the threading-holes of the thread-carrier b. In this machine the needle-tube H turns with the 40 needle-bar when the latter is turned by the crank-handle S with the feed of the machine.

It is evident that the above-described mechanism can be equally well applied to sewing-machines which work with a universal feed.

45 It is evident that the above-described me-

chanical devices may be modified without materially changing the substance of my invention. Thus, for instance, the pitman V² may be operated by means of a cam instead of a crank; or it may be operated by the action of 50 the crank-pin upon a cam-groove, if the circular movement of the crank-pin should not be found suitable for the proper operation of the machine. Similar changes may also be made in the shape of the driving-screws; and, instead 55 of the screw-threads R', a spiral groove may be cut into the rear part of the sleeve M, and a friction-roller of the sleeve H may be fitted into such spiral groove to produce the same effect as the screw-gears above described. Such 60 modifications, which are mere mechanical details, do not change the substance of my invention.

I claim—

1. The combination, with the shaft of the 65 sewing-machine, the needle-bar, and means for reciprocating the latter, of a thread-carrier and mechanism independent of the needle-bar and receiving motion from the aforesaid shaft for oscillating said carrier around the needle, substantially as described.

2. The combination of a hollow shaft or sleeve supported on the shaft which directs the feed movement, mechanism for reciprocating the said hollow shaft or sleeve, a thread-carrier, and gearing for imparting an oscillating movement to the thread-carrier from the hollow shaft or sleeve, substantially as described. 75

3. The combination of the wheels N O, shaft P, crank U², pitman V², and slide-head F with 80 the hollow sleeve M, sliding upon shaft W, substantially as and for the purpose herein described.

In testimony whereof I have signed this specification in the presence of two subscribing 85 witnesses.

EMIL CORNELY.
